FIRE DOOR.

APPLICATION FILED AUG. 4, 1917.

Patented Sept. 9, 1919.

2 SHEETS—SHEET 2.

UNITED STATES PATENT OFFICE.

FRANK A. DRAB, OF CHICAGO, ILLINOIS.

FIRE-DOOR.

1,315,659.

Specification of Letters Patent. Patented Sept. 9, 1919.

Application filed August 4, 1917. Serial No. 184,384.

To all whom it may concern:

Be it known that I, FRANK A. DRAB, a citizen of the United States, residing at Chicago, in the county of Cook and State of Illinois, have invented a certain new and useful Improvement in Fire-Doors, of which the following is a full, clear, concise, and exact description, reference being had to the accompanying drawings, forming a part of this specification.

This invention relates to fire doors and its primary object is to provide a door of this type which is simple and compact in construction, cheap to manufacture and install and effective in repelling or confining fire; and one which will expand but will not buckle under abnormal temperatures.

Another object of my invention is to provide a door having a construction facilitating rapid and accurate assembly and permitting of removal of parts requiring repair in the event of damage to the parts.

Another object of my invention is to provide a door of the class referred to which is light, yet it is rigid and not liable to injury when subjected to rough use.

Other objects and advantages to be derived from my invention will appear from the following detail description and the claims, taken with an inspection of the accompanying drawings, in which—

Figure 1 is a rear fragmental elevational view of a fire door embodying the improvements of my invention;

Fig. 2 is an enlarged fragmental perspective view of one corner of the door showing the structure of one stile and the bottom rail;

Fig. 3 is an enlarged fragmental perspective view of the rear upper portion of the door;

Fig. 4 is a semi-diagrammatic view showing the hardware and guide employed on the door;

Fig. 5 is an enlarged end elevation of the upper portion of the door, supporting rollers and trackways, the latter being shown in section; and

Fig. 6 is an enlarged fragmental elevation of one corner of the door, partly in section, showing the covering for the securing bolt.

The door of my invention preferably comprises a body formed of front and rear panels 10 and 11 of corrugated material, the corrugations of the front panel lying verti-

cally and the corrugations of the rear panel lying horizontally. Between the panels 10 and 11 is supported a sheet 12 of asbestos or other fire resisting material. The door frame consists of sectionalized stiles and top and bottom rails.

The stile members are designated S and S' in their entireties, said stile members being constructed in the manner as shown in Fig. 2. As shown in said figure the stile comprises an outside section 13, formed of sheet metal, and generally L-shaped in cross-section, to provide a front portion 14 connected to the edge of the front panel 10 by means of rivets 15 or the like. The other free edge of the section 13 is bent to form a channel portion 16 which is in turn bent to form a retaining flange 17.

The inside stile section is right-angular in cross section and is designated 18 in its entirety, one margin of the stile section 18 having a retaining flange 19 similar to the flange 17 hereinbefore referred to, but oppositely disposed thereto. The portion 20 of the inside stile section 18 is connected by means of rivets 21 or the like to the rear panel 11.

An interlocking strip 22 is provided, said strip having the margins thereof bent toward each other to form interlocking flanges 23 for engagement with the retaining flanges 17 and 19 hereinbefore described. The interlocking strip 22 serves to connect the inside and outside stile sections to form the main portion of the stile as well as to connect the plates or panels 10 and 11. The reinforcing bar 24 is disposed in the space formed by the stile sections, said bar being covered with asbestos 25 or the like.

Top and bottom rails R and R' are provided, the structure of said rails being identical and best shown in Fig. 2, wherein the bottom rail is disclosed in section. The bottom rail discloses a front section 27 and a rear section 28. The front section is formed with a retaining flange 29 on its rear margin and the section 28 is provided with a retaining flange 30 on its front margin. An interlocking strip 31 similar in shape to the strip 22, hereinbefore described, is adapted to engage with the flanges 29 and 30 and maintain the rail sections 27 and 28 in connection.

The front portion of the section 27 is bent upwardly as at 32 and offset inwardly as at 33 to provide an upstanding flange 34 which

is connected to the lower margin of the front panel 10 by means of rivets 35 or the like.

A reinforcing bar 36 is disposed in the bottom rail and is covered with asbestos 37 or the like.

As is shown in dotted lines in Fig. 2 the stile and the bottom rail terminate out of contact with each other, this being for the purpose of facilitating assembling of the device. It is of course to be understood that the top rail is practically identical in construction with the lower rail, the only difference being the attachment of hangers thereto which will be set forth in detail later.

In order to reinforce the corners of the door I provide gusset plates 9, one of said plates being best shown in Fig. 3 and partly shown in Fig. 2. The gusset plate is triangular in shape and provided with flanges 39 and 40 along two edges thereof, said flanges being provided with elongated openings 41 for a purpose which will hereinafter appear. The gusset plates are adapted to seat in the corners formed by the stiles and top and bottom rails.

In order to protect the ends of the stiles and top and bottom rails and to present a finished appearance thereto, I provide a cover box at each corner, the same being best shown in Figs. 2 and 3. The box is designated B and is made of relatively thin material having three sides. Two sides of the box B are adapted to lie upon the outer stile sections and the outer portions of the rails R and R' and these sides are provided with slotted tongues 43 which are bent over the stile and rail and inwardly over the gusset plate flanges 39 and 40, said tongues being maintained in position by means of nuts 44 carried by bolts 45 which pass through the box, stile, reinforcing bar and gusset plate. At each corner of the door the structure described in the foregoing is duplicated. The bolts pass through the slots 41 formed in the flanges 39 and 40 of the gusset plate. As best shown in Fig. 2 fusible washers 46 are interposed between the nuts 44 and the flanges 39 and 40 of the gusset plate, said washers being adapted to melt when a predetermined abnormal temperature is reached to permit expansion of the door body without buckling of the same. This prevents irreparable damage to the door, the washers being easily renewed after a fire to place the door in condition for continued use.

To further reinforce the box structure and gusset plates the bolts 48 are provided, said bolts passing through the box structure, front portion 14 of the stiles, sheets 10 and 11 and the asbestos 12 and the gusset plates, said bolts being maintained in position by a suitable nut, as shown at 49 in Fig. 3. The door as shown is adapted for use as a gravity-closing door and therefore in view of

the inclination of the trackway the upper rail of the door is inclined relative to the bottom rail as best shown in Fig. 1.

The running gear of the door comprises a pair of bracket members 50 and 51 bolted at 52 and 53 to the door structure, back-up plates 54 serving to distribute the pressure of the bolts 52 and 53 and prevent mutilation of the inside sheet 11. The upper ends of the bracket are bent into U-shape formation to form bearings which support grooved rollers 56. The rollers 56 are adapted to run on a trackway comprising a flat bar 57 mounted on spacing supports 58 and bolts 59. Track binders 60 are provided on top of the top rail of the door and are adapted to project above the bottom margin of the trackway 57 so that in the event of fire and when the door expands raising the rollers from the trackway the binders 60 will serve to engage the trackway and prevent the door from falling away from its opening. Bolts 61 pass through the track binders and the upper ends of the back-up plates 54.

The hardware in use on my improved door comprises a front and rear binder both of which are best shown in Fig. 4. In Fig. 4 the door has been shown in dotted lines and designated D in its entirety, an angle piece 63 being mounted on the inner portion of one of the stiles and adapted to engage with the inside or rear binder 64. The binder 64 comprises a flat plate bent at right angles and adapted to be fastened to one side of the door frame 65, one free end of the binder 64 being offset at 67 and in spaced relation to the door frame so that the angle piece 63 may engage between the door frame and the offset portion when in closed position. A front binder comprises a flat plate 68 bolted or otherwise secured to the other side of the frame of the door and provided with an offset portion 69 to embrace the door when in the closed position, as best shown in Fig. 4.

The door is provided with suitable handles 70 or may be operated by any automatic thermally controlled mechanism or the like. After the door has been assembled, a plurality of rivets are inserted through the front and rear sheets of the door to prevent said sheets from buckling in the center, said rivets are designated 71.

In Fig. 6 a portion of one corner of the door is shown, a portion of the side being in section to illustrate the manner of protecting the bolt and to present a finished appearance to the door. This embodies a strip of metal 90 inserted between the asbestos covering of the reinforcing bar and the outer wall of the stile and covering the bolt. The plate is soldered at the opening so as to present a substantially smooth exterior surface.

From the foregoing description it will be seen that I have provided a simple, durable

and efficient fire door which is cheap to manufacture and install, the various parts thereof being readily removable in the event of damage thereto for the purpose of repair or 5 inspection. The disposition of the corrugations of the front and rear sheets at right angles to each other permits a circulation of air through the door at all times as well as providing a door which cannot warp, is 10 more rigid than usual with this type of door and is light in weight. I direct particular attention to the spacing of the lower margin of the front panel from the bottom rail, so that any water entering at the top of the 15 door and gaining access to the interior thereof will easily drain off the lower rail. This feature obviates the difficulty now encountered in sheet metal doors which quickly causes rust to accumulate at the base of the 20 door resulting in deterioration and decay.

In assembling the door the stile sections are first fastened to their respective panels. The asbestos sheet is placed on the front panel, the former being laid flat on a suitable support and the rear panel is placed upon the front panel. The interlocking strips 22 are then engaged with the stile sections to connect the same and the panels are then ready to receive the top and bottom 25 rails. The top and bottom rails are then riveted to said panels and the door is raised to receive the enforcing plates 24 and 36. Of course, it will be understood that, if desired, the sections of the top and bottom 30 rails may be applied to the front and rear panels before the first step of assemblage. The connection between the stile sections and the sections of the top and bottom rails permit a convenient method of assembly of 35 the door and when the door is assembled the stiles and top and bottom rails present smooth surfaces so that the door may be applied directly for use in an opening or for use over an opening, as illustrated in 40 the drawings.

On the outer panels of the door I place a standard piece of hardware in the form of a strip 92 inclined parallel to the top margin of the door, said strip being shown in 45 dotted lines in Fig. 1, the roller being shown in dotted lines in Fig. 4. This is a conventional form of guide roller now in wide use and a further showing would be superfluous, as those skilled in the art are thoroughly 50 familiar with the structure and the use of the same.

I am aware the doors of this class have been invented and patented heretofore, but I have designed a door in which the rail 55 and stile structures have been constructed to facilitate assemblage and cheapen the manufacture, as well as provide a door

which is readily applicable for use in connection with any opening and with any automatic closing mechanism.

65

While I have shown and described my invention as embodying certain detail structure, I desire that it be understood that I reserve the right to make changes in such structure as do not depart from the spirit 70 and scope of the invention as claimed.

I claim:

1. The combination with a pair of juxtaposed panels, of a pair of stiles composed of inside and outside sections, the outside section having a front portion connected to the front panel, the inner portion of said section having a locking flange formed thereon, the inside section having a locking flange formed thereon for alignment with 75 the first flange on the outside section, an interlocking strip to engage said flanges, and connected sections to form the complete stile and said inner section being connected to said inner panel.

85

2. The combination with juxtaposed corrugated panels of a rail structure composed of a front portion substantially right-angular in cross section and formed with an offset upstanding flange for engagement with 90 the outer panel, a rear portion having an upstanding flange for engagement with the inner panel, locking flanges formed on the free margins of said portions, an interlocking strip for connection with said flanges 95 to form the rail, and a reinforcing bar within in said rail.

3. In a door of the kind described, two parallel spaced panels, hollow stiles at the sides of the door and hollow rails at the top 100 and bottom of the door, interlocking flanges and removable strips joining the edges of the panels within said stiles and rails, the ends of the stiles and rails at the corners of the door being cut away to afford openings 105 for the insertion of the locking strips, and corner forming members embracing the stiles and rails at the corners of the door to complete the door.

4. In a door of the kind described, two 110 parallel spaced panels, hollow stiles at the sides of the door and hollow rails at the top and bottom of the door, reinforcing bars within said stiles and rails, the two panels having opposed locking flanges on their 115 edges within said stiles, interlocking strips to engage said flanges, the meeting ends of the stiles and rails being cut away to permit the insertion of said interlocking strips, and sheet metal corner members for completing 120 the door and closing said openings.

In witness whereof, I hereunto subscribe my name this 24th day of July, A. D. 1917.

FRANK A. DRAB.
